CLAIM

The ornamental design for a cutting body for rotors to break up organic matter, especially cutting body for use in rotors to break up cotton cultures, as shown and described.

DESCRIPTION

FIG. 1 shows a perspective view of a first embodiment of a cutting body.

FIG. 2 shows a top view of the embodiment of FIG. 1.

FIG. 3 shows a first side view of the embodiment of FIG. 1, wherein the second side is a mirror image of the first side.

FIG. 4 shows a back view of the embodiment of FIG. 1.

FIG. 5 shows a front view of the embodiment of FIG. 1; and, FIG. 6 shows a bottom view of the embodiment of FIG. 1.
